UNITED STATES PATENT OFFICE.

WILLIAM C. STEFFAN, FRANK B. ACKERMANN, AND WALTER J. GREINER, OF CHICAGO, ILLINOIS.

PENCIL.

Application filed October 2, 1920. Serial No. 414,165.

This invention relates to pencils of the screw type and an object of the invention is to provide a pencil which is simple in construction, durable and efficient in operation, embodying a longitudinal movable feeding stem for feeding the lead, which is operated by rotation of the cap upon the butt end of the pencil.

A further object of the invention is to provide a tip which is split longitudinally and has a split constricted portion providing a grip upon the lead of the pencil to prevent it from slipping or moving during the use of the pencil.

Another object of the invention is to provide a lead feeding stem carrying barrel which is provided with a constricted portion flattened to prevent rotation of the rectangular lead feeding stem.

Other objects of the invention will appear in the following description taken in connection with the accompanying drawings wherein:

Fig. 1 is a side elevation of the improved pencil.

Fig. 2 is a longitudinal section through the pencil.

Fig. 3 is an enlarged longitudinal section through the tip showing the lead projected.

Fig. 4 is a fragmentary view of the tip greatly enlarged to illustrate the manner of splitting it for providing a grip upon the lead.

Fig. 5 is a cross section through the tip taken on line 5—5 of Fig. 4.

Fig. 6 is a view partly in side elevation and partly in section of the crown of the pencil.

Fig. 7 is an enlarged longitudinal section of the barrel of the pencil.

Fig. 8 is an enlarged longitudinal section through the casing of the pencil.

Fig. 9 is a view partly in side elevation and partly in section of the feeding stem and feed screw.

Fig. 10 is a longitudinal section through the eraser clutch sleeve and feeding sleeve of the pencil.

Fig. 11 is a cross section through the eraser clutch sleeve taken on line 11—11 of Fig. 10.

Fig. 12 is an enlarged cross section taken on line 12—12 of Fig. 9.

Fig. 13 is a greatly enlarged section taken on line 13—13 of Fig. 9.

Fig. 14 is an enlarged fragmentary sec-

tional view of the upper portion of the pencil illustrated in Fig. 2 of the drawings.

Fig. 15 is a sectional detail view of the pencil embodying the invention taken substantially on line 15—15 of Fig. 2.

Referring more particularly to the drawing 1 indicates a casing of the pencil which may be made of hard vulcanized rubber, silver or any desired metal and which is cylindrical in shape, having its butt end reduced in diameter and externally threaded as at 2 while its tip end is internally threaded as at 3, being slightly reduced in diameter as at 4 which reduced portion tapers away from the longitudinal axis of the casing towards the butt end thereof providing an inclined or tapered reduced portion which receives thereover the butt end of the tip 5 of the pencil which butt end is recessed as at 6 to snugly fit the reduced portion of the casing 1 and the tip 5 which is substantially conical in shape is provided with an enlargement 7 near its butt end internally threaded and providing a shoulder 8 against which the tip end of the casing 1 abuts when the tip and casing are properly connected. The threads on the enlargement 7 threadably engage the external threads upon the casing attaching sleeve 9 which is soldered or otherwise suitably attached to the barrel 10 of the pencil. The barrel 10 of the pencil extends longitudinally through the casing 1 and projects into the tip 5 as clearly shown in Fig. 2 of the drawings, forming a retainer for the lead 11 and also a retainer for the feeding stem 12. The sleeve 9 is threadably engaged in the interior threaded portion 3 of the casing 1 and serves to connect the barrel 10, tip 5 and casing 1 at the tip end of the pencil. The sleeve 10 is provided with a constricted portion 13 intermediate its ends which is substantially rectangular in cross section or is provided with flattened portions to engage opposite flattened sides of the feeding stem 12 to prevent rotation of the feeding stem and cause it to be moved longitudinally upon rotation of the feeding sleeve 14. The feeding sleeve 14 is internally threaded as at 15 to receive the feed screw 16 and for moving the stem 12 longitudinally in the barrel 10 upon rotation of the sleeve 14. The feed screw 16 is provided with a rectangular recess 17 in its inner end which receives therein the reduced rectangular end of the feeding stem 12 to

connect the feeding stem and feed screw. This may be a driven joint to provide the necessary friction to maintain connection between the feed screw 16 and feeding stem 12. The feeding stem 12 has its free end reduced as shown at 18, and preferably rounded or cylindrical in shape for fitting within the cylindrical portion 19 of the barrel 10 and for properly engaging the inner end of the lead 11 to move this lead outwardly upon outward movement of the stem 12.

The major portion 20 of the barrel 10 is cylindrical in shape and it slidably receives the feeding sleeve 14 as clearly shown in Fig. 2 of the drawings. The feeding sleeve 14 extends through the web 21 in the eraser clutch sleeve 22 and it has its inner edge upset or spun as shown at 23 to provide firm connection between the feeding sleeve 14 and clutch sleeve 22. The inner surface of the web 21 forms an abutment for the butt end of the barrel 10. The eraser receiving portion of the sleeve 22 is split longitudinally as shown at 24 and is constricted at its outer open end to frictionally grip and confine the eraser 25 therein. A crown 26 is threaded over the external threaded reduced end 2 of the casing 1 and it is provided with an internal shoulder 27 which abuts the butt facing side of a ring 28 formed on the sleeve 22. The tip facing side of the ring 28 abuts the butt end of the casing 1 and thus when the crown 26 is threaded in place it securely confines the eraser clutch sleeve 22, feeding sleeve 14, and barrel 10 in position within the casing preventing movement of the feeding sleeve 14 towards the butt end of the pencil during its rotation and consequently forcing the feeding stem 12 towards the tip of the pencil for forcing the lead 11 through the opening 29 in the apex of the tip. The artistic cap 30, of any approved design, is slidably mounted upon the eraser receiving portion of the clutch sleeve 22 and houses the eraser 25, it being necessary to remove this cap when it is desired to use the eraser.

The tip 5 is split longitudinally from its apex towards its base as shown at 31 and this split is constricted at the apex of the tip for providing a firm grip upon the lead 11, so as to prevent the lead from slipping or moving about during use of the pencil and limiting the liability of breaking the lead during the use of the pencil.

A spacing collar 32 is wedged or soldered on the major portion 20 of the barrel 10 intermediate its ends and serves the dual purpose of maintaining the barrel axially spaced within the casing 1 and forming an inner end for the extra lead receiving magazine 33. The extra lead receiving magazine is formed within the casing 1 about the barrel 10, at the butt end of the pencil, and access to the lead is permitted by unscrewing

the crown 26 and withdrawing the sleeves 22 and 14 from the butt end of the casing.

If it is so desired a spring clip, as indicated at 34 may be attached to the casing 1 to prevent the loss of the pencil.

It is, of course, to be understood that the invention may be constructed in various other manners and the parts associated in different relations and therefore, we do not desire to be limited in any manner except as set forth in the claims hereunto appended.

Having thus described our invention what we claim is:

1. In a pencil, a casing, a barrel axially within said casing and having a constricted flattened portion, a lead feeding stem movable in said barrel and held against rotation by said constricted flattened portion, means for feeding said stem, a tip, and an attaching sleeve soldered on said barrel and connecting said casing, barrel and tip. 80

2. In a pencil, a casing, a barrel, an eraser clutch sleeve extending into the butt end of said casing and forming an abutment for the butt end of said barrel, a ring on said clutch sleeve, and a crown engaging the said casing and ring for confining said clutch sleeve, casing and barrel in proper relation. 90

3. In a pencil, a casing, a barrel, an eraser clutch sleeve forming an abutment for the butt end of said barrel, means for confining said eraser sleeve in position relative to said casing, said sleeve provided with an eraser receiving portion having longitudinally extending slits, said slits converging as they extend towards the outer end of said sleeve for frictionally gripping an eraser. 95

4. In a pencil a casing, a barrel, a tip, an attaching sleeve on the barrel connecting the casing, barrel and tip, an eraser clutch sleeve extending into the butt end of the casing forming an abutment for the butt end of said barrel, a ring on the clutch sleeve, and a crown engaging said casing and ring for confining the clutch sleeve, casing and barrel in place. 105

5. In a pencil, a casing, a barrel, a tip, an attaching sleeve on the barrel connecting the casing, barrel and tip, an eraser clutch sleeve extending into the butt end of the casing forming an abutment for the butt end of said barrel, a ring on the clutch sleeve, a crown engaging said casing and ring for confining the clutch sleeve, casing and barrel in place, a spacing ring on said barrel intermediate its ends and forming an inner partition within the casing to provide an extra lead receptacle. 115

6. In a pencil, a casing, a barrel axially within said casing and having a constricted flattened portion, a lead feeding stem movable in said barrel and held against rotation by said constricted flattened portion, means for feeding said stem, a tip, and an attaching sleeve soldered on said barrel and con- 125

necting said casing, barrel and tip, said tip provided with diametrically spaced longitudinally extending slits having their sides converged towards the end of the tip for frictionally gripping the lead.

7. In a pencil, a casing, a barrel, a substantially conical tip, an attaching sleeve on said barrel connecting said casing, barrel and tip, said tip provided with longitudinally extending slits having their sides converging towards the apex of the tip, an eraser clutch sleeve extending into the butt end of the casing and forming an abutment for the butt end of said barrel, a ring on said clutch sleeve, a crown engaging said casing and ring for confining the clutch sleeve, casing and barrel in place, said clutch sleeve provided with a plurality of longitudinally

extending slits having their sides converging as they extend towards the outer end of the sleeve for frictionally gripping an eraser.

8. A pencil of the class described including a casing having a reduced end portion, a barrel confined in the casing, an eraser clutch sleeve extending into the butt end of the casing and forming an abutment for the butt end of the barrel, a ring on the clutch sleeve, and a crown mounted upon the reduced end portion of the casing and engaging the ring for confining the clutch sleeve, casing and barrel in proper relation.

In testimony whereof we affix our signatures.

WM. C. STEFFAN.
